UNITED STATES PATENT OFFICE.

GEORGE M. BARD, OF CHICAGO, ILLINOIS.

ROTARY ENGINE.

No. 889,188.

Specification of Letters Patent.

Patented June 2, 1908.

Application filed March 5, 1906. Serial No. 304,157.

To all whom it may concern:

Be it known that I, GEORGE M. BARD, a citizen of the United States, residing at Chicago, in the county of Cook and State of Illinois, have invented certain new and useful Improvements in Rotary Engines, of which the following is a specification.

The object of my invention is to produce a simple yet efficient rotary engine wherein 10 the rotating eccentric part may be provided with a continuous surface without openings.

The accompanying drawings illustrate my invention: Figure 1 is an axial section, Fig. 2 a transverse section on line 2 2 of Fig. 1; 15 Fig. 3 a sectional detail of the connection between the vane and eccentric, and Fig. 4 a section on line 4 4 of Fig. 3.

In the drawings, 10 indicates a cylinder formed in any desired manner preferably by 20 means of similar arc sections 11 provided at each end with radial wings 12 between which are clamped U-shaped portions 13, thus forming radial pockets 15 opening into the cylinder. Mounted in the pockets 15 so as 25 to reciprocate therein are vanes 16 which are supported at their edges in radial slots or grooves 17 formed in the arms of a spider 18 one of which is secured in each end of the cylinder 10 and held against rotation. 30 Journaled in the two spiders 18 is a shaft 19 which carries an eccentric body 20 adapted to engage the cylinder 10 at one point and to be engaged by the inner ends of the vanes 16. The spiders 18 lie immediately adjacent the 35 ends of the eccentric 20 and secured to the shaft 19 immediately outside of each spider

18 is a plate 21 which fills the end of the cylinder and rotates with the shaft 19. Each end of the cylinder, outside of the plate 21 is 40 closed by a suitable cap or head 22 which lies a short distance from the adjacent plate 21 so as to provide a steam space 23. Formed through one of the plates 21 are inlet ports 23' (one or more) and formed 45 through the other plate 21 are exhaust ports 24 (one or more). The inner ends of the vanes 16 are provided with any suitable means for forming a steam-tight joint with the surface of the eccentric body 20. In the 50 construction shown the vane is provided at its inner end with a socket 25 adapted to re-

ceive a shoe 26 which shoe may oscillate in the socket 25 so that its inner wearing surface may at all times lie properly against the surface of the eccentric. It is desirable that 55 some means be provided to positively reciprocate the vane 16 in both directions by the rotation of the eccentric body 20, and for this purpose each inner corner of the vane is provided with an extended lip 28 which overlaps the eccentric and carries a pin 29 upon which is pivoted a shoe 30 lying in an angular groove 31 formed in the adjacent end of the eccentric body, the arrangement being 60 such that as the eccentric is rotated the vane 65 will be positively reciprocated, and shoe 26 will remain in contact with the surface of the eccentric.

In operation, with the parts in the position shown in Fig. 2 steam will enter 70 through ports 23 and cause a rotation of the eccentric 20 in the direction indicated by the arrow. As the eccentric advances the plates 21 advance with it and when ports 23' pass the next forward vane 17 steam is admitted 75 into the space immediately in front of said vane. In the meantime steam is exhausted through the exhaust ports 24, said exhaust ports being carried around as the eccentric rotates. It will be seen, therefore, that 80 there is a continuous admission of steam into successive portions of the cylinder and a continuous exhaust from successive portions of the cylinder in immediate advance of those portions into which steam is being 85 admitted.

I claim as my invention:

1. In a rotary engine comprising a cylinder, an eccentric body rotatably mounted therein, a vane projected into said cylinder 90 and coacting with the eccentric body, a pair of port plates mounted in the cylinder and rotating with the eccentric body, and having inlet and exhaust ports respectively communicating continuously with the interior of 95 the cylinder.

2. In a rotary engine, the combination, with a cylinder, an eccentric body rotatably mounted therein, and a vane projected into said cylinder and coacting with said eccentric body, of a stationary spider mounted in 100 each end of said cylinder and provided with

guides supporting the edges of said vanes, a port plate mounted in the cylinder outside each spider and rotating with the eccentric, the ports of said plates being continuously in communication with the cylinder and caps for the ends of the cylinders.

5 In witness whereof, I have hereunto set

my hand and seal at Indianapolis, Indiana, this 14th day of December, A. D. one thousand nine hundred and five.

GEORGE M. BARD. [L. S.]
